FOLDING-MACHINE.

1,270,753.

Specification of Letters Patent. Patented June 25, 1918.

Application filed October 12, 1912. Serial No. 725,381.

To all whom it may concern:

Be it known that I, PERLEY RICHMOND GLASS, a citizen of the United States, residing at Brookline, county of Norfolk, State of Massachusetts, have invented an Improvement in Folding-Machines, of which the following description, in connection with the accompanying drawing, is a specification, like characters on the drawing representing like parts.

This invention relates to machines for folding or turning over the edges of a sheet material such as leather used in the manufacture of boots and shoes. In such manufacture it is customary thus to fold the exposed edges of the finished shoe so as to prevent exposing a raw edge. In such case the edge to be folded is usually beveled or skived so that the thickness at the fold when the folding or the turning operation is complete is practically the same as the thickness of the body of the sheet. The skived edge is covered with cement so that, when it is subsequently folded over and pressed, it is permanently secured in place.

The object of the invention is to present a machine for doing this class of work in which the edge is folded or turned a little at a time and progressively and in which the fold may lie smoothly at any curved portions of said edge.

The nature of the invention will appear more fully in the accompanying description and drawings and will be defined in the appended claims.

The drawings illustrate a machine to carry into effect the objects of the invention, the said machine embodying the principles thereof and being the best means at present known for that purpose. It is to be understood, however, that the particular construction illustrated is merely illustrative of the invention and is not exhaustive.

In the drawings—

Fig. 1 is a front elevation of the machine.

Fig. 2 is an isometric view looking down on the central portion of the work plate and showing the instrumentalities for operating on the material.

Fig. 3 is a rear elevation of the parts shown in Fig. 2.

Fig. 4 is an isometric view of the upper

portion of the machine frame with the work plate removed and showing a number of the instrumentalities and connections.

Fig. 5 is an isometric detail of the supporting guide for the folding finger.

Fig. 6 is an isometric detail of the folding finger and its operative connections.

Fig. 7 is an isometric detail of the fold presser and its operative connections.

Fig. 8 is an isometric detail taken at right angles to Fig. 7 and showing only the upper parts shown in said figure.

Fig. 9 is an isometric detail from underneath the machine showing the knee lever and connections to extend to the snipper mechanism.

Fig. 10 is a side elevation partially in cross-section of the feeding mechanism.

Fig. 11 is an isometric detail of the snipper knife and its operative connections.

Fig. 12 is an isometric view of the central portion of the work plate and parts supported thereabout showing the stock or material in position and about to be acted on by the snipper.

Fig. 13 is an isometric detail showing the stock held by the complementary pressing members after folding.

Fig. 14 represents a shoe vamp with the inner edge folded as by a machine of this invention.

Fig. 15 represents the rear portion of a shoe upper with its edge folded as by a machine of this invention.

Fig. 16 is a detail perspective on an enlarged scale showing the formation of a pucker.

The machine as illustrated comprises a substantially circular base plate 1, adapted to be secured to a rest upon a work table 2. A turret shaped frame or casing 3 supports or contains the bearings for various portions of the mechanism and incloses the main operative parts. This casing is pivoted to the base at 4 in the rear and is locked to the base in front by a nut 5 threaded on a shaft 6 having a ball-and-socket connection 7 with the base and extending between lugs 8 projecting from the said casing 3. This enables the casing to be tipped back exposing the interior parts to view and enabling them to be cleaned and any adjustment thereof readily to be made.

The casing 3 terminates on its top with the flat surfaces 9 as shown in Fig. 4 and a circular work plate 10 shown in Fig. 1 is secured in place on top of these flat surfaces by screws extending into the threaded holes 11.

The casing 3 is provided with bearings in which is mounted the main shaft 12 which is provided with a hand wheel 13 and a friction member 14 fast thereon. Suitable pulleys 15 and 16 are loosely mounted on said shaft, and when brought into frictional contact with the friction member 14 rotate the said shaft from any suitable source of power. The pulleys are clutched to the friction member by means of a lever 17 fulcrumed at 18 on the base plate 1, and which may be connected to the usual foot treadle not shown, so that upon rocking the said lever the clutching operation is effected.

A yielding work support 19 is provided to aid in the support of the stock when required adjacent the folding mechanism. The folding mechanism in the preferred form illustrated comprises several elements which by their co-operative action turn or fold the edge of the stock little by little progressively and set the fold. These instrumentalities, omitting for the present the snipper mechanism and the guiding mechanism, which will be considered later, comprise first, means to define and initiate the fold throughout a small section of the edge, and second, means to complete and set the fold.

The means for defining and initiating the fold as herein illustrated comprises a fold guide or creaser 20 and a folding finger 21 (see Fig. 6), the fold guide holding the stock and defining the line about which the edge is turned by the folding finger. The means for completing and setting the fold comprises a pressing block 22 on which the stock 45 rests and the fold presser 23 which completes the turning of the edge and then clamps the folded edge to the block 22, completing the fold which is thereby set, and by an increased pressure subsequently given 60 to said supplemental members.

The work support 19 in its normal upper position has its surface level with the surface of the work plate 10, and is slightly beveled off in front and at the left to enable 55 the stock to ride easily into place. The extremity or edge of the fold guide or creaser 20 normally stands above the edge 24, and that portion of the stock projecting beyond or to the right of this edge is folded 60 back on a line defined by the fold guide. This work support is mounted to yield vertically to aid in taking care of the passage of stays or thickened portions through the machine, and it is also given an up and 65 down movement to bring it into position,

and then remove it therefrom to allow the feed to take place. A suitable means for securing this operation is illustrated more particularly in Fig. 4. As therein shown, the yielding work support 19 is formed on 70 the end of a lever 25 fulcrumed on a shaft 26 journaled in bearing lugs 27 projecting from the front portion of the frame 3 near the top. The forwardly projecting end 28 of the lever 25 extends through to the exterior of the frame within reach of the operator. The shaft 26 has clamped thereon by means of the split collar 29 a frame 30, the forward portion 31 of which projects beneath a lug on the forward arm of the 80 lever 28 and is provided with a vertically adjustable stop screw 32, while the rear portion 33 of this frame projects beneath a lug on the rear arm of the lever 25 and carries a vertical bearing 34 in which is mounted 85 a vertically yielding pin 35. The shaft 26 has also clamped thereto a crank arm 36 connected by a link 37 with a forward end of a forked arm 38 pivoted on a shaft 39 secured in the rear of the casing parallel 90 with the main shaft 12. This forked arm 38 spans an eccentric 40 carried by the main shaft. The forked arm 38 is shown as provided with a gib 41 vertically adjustable by means of the set screws 42, to take up 95 wear and prevent lost motion.

It will thus be seen that from the rotation of the main shaft 12 the eccentric 40 rocking the forked arm 38 will transmit its motion through the link 37, the arm 36, the shaft 26, the frame 30 and the lever 25, to the work support 19, moving it into upper and lower position at the required times. Whenever it is desired to depress the work support by hand the operator raises the forward end 28 of the lever 25 and the spring 100 pressed pin 35 allows the lever to rock independently of the mechanism for positively operating it. This same yielding connection enables the work support to give whenever a 105 stay or a thick portion of the stock passes over it.

The stock is positioned during the initiating of the fold by the element herein termed a "fold guide" and which, as shown at 20, 115 comprises a finger adapted to rest on top of the stock with its edge above and slightly back of the edge 24 of the work support, so that when the stock is turned back the edge of the fold guide will fit within the crease 120 and define the line of fold. This fold guide is also mounted to yield to allow the insertion of the stock between it and the work support, and to allow the passage of stays or unusual thicknesses and for this purpose 125 it yields both vertically and in a direction away from the line of fold. In the construction shown this fold guide is curved to the left to allow for the width of the folded edge, and presents a vertical shank 43 mounted to slide 130

in a head 44 pivotally secured at 45 in a short overhanging arm 46 secured to the work plate 10. A set screw 47 passes through the overhanging arm 46 and abuts against the lower end of the head 44, while a spring pressed pin 48 mounted in a chambered upper portion 49 of the arm 46 abuts against the upper end of the head 44. A spring pressed pin 50 is mounted in a chambered lug 51 forming a part of the head 44 and rests against the top of the curved portion of the fold guide, thus holding it yieldingly downward. A lever 52 having a finger piece 53 is fulcrumed on the pivot 45, and has one end 54 normally resting on a seat in the head 44 and beneath a set screw 55 located in a rectangular projection from the shank 43. The spring pressed pin 50 normally holds the fold guide 20 in its lowermost position with the lever 52 in engagement with the end of the set screw 55, so that by adjusting the set screw 55 the limit of the lowermost position of the fold guide may be adjusted.

25 In order to insert the stock or to allow the passage of a stay or other unusual thickness, the operator depresses the lever 52 by pressing on the finger piece 53, thus first elevating the fold guide 20 against the action of the spring pressed pin 50 and then rocking the fold guide 20 away from the line of fold about the pivot 45 against the action of the spring pressed pin 48. These spring pressed pins may be adjusted by the set screws shown to give any required amount of pressure, and owing to the curved shape of the edge of the fold guide the fold guide itself will yield automatically at the required times and under the particular conditions existing.

40 The edge of the stock is given its initial fold when held in position by the fold guide by means of the folding finger 21, which is provided with a rounded edge facing the edge of the guide 20, and is of such width that but a small section of the length of the edge is turned over at one time.

45 This folding finger is, in the construction shown, given a movement back and forth close to the edge of the guide 20, and slightly inclined with respect to the plane of the work plate, so that in its initial fold the edge is turned back to considerably more than 90 degrees.

50 The folding finger may be given this movement by the means herein illustrated. In this form a supporting guide block 56 is secured by set screws 57 to a projecting portion 58 of the casing or frame 3. The shank 59 of the folding finger 21 is mounted to slide in a way or recess 60 formed in the face of the guide 56, and so located that as the shank 59 moves therein the folding finger 21 will be carried past and close to the edge of the guide 20 in an inclined direc-

tion. The shank 59 is held in place by a plate not shown secured to the guide 56 by screws not shown entering the holes 61.

55 Rectilinear movement is imparted to the folding finger by connections to a forked arm 62 pivotally mounted on the shaft 39 and engaging an eccentric 63 of suitable form mounted on the shaft 12. Suitable connections extend from the arm 62 to the folding finger 21 to allow of the required movement taking place and, as shown, comprise a U-shaped link 64 pivoted at 65 to a lug 66 formed on the shank 59; an H-shaped link 67 pivoted in turn to the link 64 at its upper end; and a pin 68 secured to the upper forward end of the arm 62 and pivoted to the lower end of the H-shaped link 67. It will thus be seen that upon rotation of the shaft 12 the arm 62 will be rocked and through the connections described will reciprocate the folding finger 21 past and close to the edge of the guide 20 in an inclined direction, thus initiating the fold and turning the edge back considerably more than 90 degrees about the fold guide 20.

60 The next step is to complete and set the fold and to feed the stock forward. In this machine both of these functions are performed by the same elements. The fold presser 23 moves down completing the turning of the fold and clamping the folded edge against the pressing block; then these complementary members gripping the stock move rearwardly, feeding the goods along. The clamping action at first is only sufficient to 100 complete the fold and hold the stock for feeding. The heavy pressure does not come until after the feed has progressed to such an extent as to prevent any stretching of the stock which would take place if heavy 105 pressure were given close up to the folding instrumentalities already described.

65 The pressing block is vertically rigid, but the co-operating fold presser is under spring pressure which allows it automatically to 110 take care of any variation in the thickness in the stock and to yield in passing over stays or seams. The pressing block 22 is formed as a part of the slide 69 (see Fig. 4) which slides back and forth in the ways 70 115 formed in the top of the casing or frame 3. The fold presser 23 is pivoted at 71 in a bearing plate 72 secured to the under side of the slide 69 (as shown in Fig. 7), so that it travels back and forth with the slide in 120 unison with the pressing block. The fold presser is swung about its pivot to move over, complete the fold and clamp the folded edge upon the pressing block by suitable means such as herein illustrated. A lever 125 73 is fulcrumed on the pivot pin 71 and carries in one arm a screw 74 abutting against the depending shank 75 of the fold presser, while a spring 76 connects the said shank to the said lever arm. The opposite arm of 130

the lever 73 has a universal connection with a forked arm 77 pivoted on the shaft 39 and engaging an eccentric 78 of suitable form carried by the shaft 12. The universal connections referred to comprise as herein illustrated a swivel link 79 pivoted at its upper end to a block 80 pivoted on the lever 73 and at its lower end to a pin 81 secured in and projecting from the arm 77. It will thus be seen that when the shaft 12 is operated the arm 77 will be rocked and through the connections described will rock the fold presser on its pivot causing it to complete the fold and clamp it against the pressing block, the spring 76 allowing the fold presser to yield sufficiently to take care of seams, stays or varying thicknesses of stock. The eccentric 78 is so shaped that after the fold presser and pressing block are clamped and begin to feed backwardly, increased pressure is applied, setting and securing the fold without danger of stretching the stock.

The feed of the stock is secured by movement of the slide 69 upon which the pressing block and the fold presser are both mounted. When the folding operation takes place this slide is in its forward position with the pressing block close to the work support, and thereafter it is moved rearwardly to an adjustable and required extent by suitable mechanism which may be adjusted while the machine is in operation, thus allowing the feed to be varied by the operator as required. In going around curves the feed is lessened according to the degree of curvature, while on straight portions it is lengthened to increase the rapidity of the operation. The limits of the feed may also be adjustably fixed so that as the feed is being varied during the operation of the machine it will not pass outside of these limits.

A suitable mechanism for this purpose is illustrated. It comprises a forked arm 82 (see Fig. 10) pivoted on the shaft 39 and engaging a cam 83 of suitable shape carried by the shaft 12.

A bell crank lever 84 is fulcrumed at 85 to the casing or frame 3. One arm of the bell crank lever 84 carries a stud 86 on which is journaled a block 87 sliding vertically between depending projections 88 of a plate 89 adjustably secured by the set screw 90 longitudinally of the slide 69.

The other arm of the bell crank lever 84 is connected by a link 91 to the arm 82. This connection at the lower end of the link 91 is an adjustable one, the arm 82 having a curvilinear slot 92 for that purpose, in which rides a stud 93 projecting from the lower end of the link. Suitable means are provided for adjusting the stud 93 longitudinally of the slot 92 to secure the results already pointed out.

For the above purpose a bell crank lever

is fulcrumed at 94 and has a forked arm 95 projecting upwardly and engaging the stud 93, while its other arm 96 projects out through a slot 97 at the front of the casing or frame. The upper and lower movement of the arm 96 is adjustably limited by pins 98 inserted in holes in the flange 99 at the front of the casing.

It is desirable to adjust the length of the feed during the operation of the machine as already explained, and for that purpose mechanism is provided by which the bell crank lever 95-96 may be shifted by a treadle connection 100. This connection 100 is secured to a lever 101 fulcrumed at 102 to the base plate and engaging at its forward end the arm 96 of the bell crank lever. It is desirable that this connection shall be detachable in order that the casing 3 may be readily swung back on its pivots 4. For that purpose a sleeve 103 is mounted on the arm 96 and has a lug 104 projecting beneath the lever 101. A spring 105 normally projects the lug 104 beneath the lever 101, but allows the sleeve to be drawn outwardly releasing the lever when desired. It will thus be seen that the feed slide 69 may by the adjusting screw 90 be set at the desired position longitudinally and then that upon the operation of the shaft 12 the slide 69 will be given a backward and forward reciprocation by means of the mechanism described; that by means of the pins 98 the forward and backward limit of this movement may be fixed as desired; and that by means of the treadle connection 100 this feeding movement may be varied at will while the machine is in operation.

Suitable means are provided for guiding the stock into position between the folding instrumentalities, and for that purpose there is herein provided a fixed gage 106 (see Fig. 2) and a co-operating yielding presser gage 107. The fixed gage 106 is longitudinally adjustably secured by means of the set screw 108 in the work plate 10. The yielding presser gage 107 is formed on the end of a lever 109 fulcrumed at 110 on the U-shaped projection 111 from the side of the overhanging arm 46 above the work plate 10. A leaf spring 112 secured to the projection 111 rests upon the lever 109 and yieldingly holds the presser gage 107 downwardly, its downward movement being limited by contact with the shoulder 113 on the fixed gage (as shown in Fig. 12). The exterior of the fixed gage is curved from the shoulder 113 downwardly to the base, and the under surface of the yielding presser gage is correspondingly curved and also curved upwardly. When the yielding gage rests upon the shoulder the stock is pushed up over this curve until its edge contacts with the yielding gage, thus presenting the stock partially curved and gaging

the amount to be folded. Variations in the width of the fold thus gaged are secured by substituting fixed gage members 106 of different dimensions. The yielding presser 5 gage yields or is moved by the operator when stays, seams or other obstructions come along.

When the edge is being turned or folded about a curve, especially about a concaved 10 curve, it is necessary to slit or snip that portion of the edge folded over, and for that purpose the machine is provided with snipping means which are thrown into action preferably by the knee of the operator 15 whenever necessary.

The snipping mechanism, as herein shown, comprises a movable snipper knife 114 and a fixed co-operating blade which is here 20 formed at the back of the fixed gage 106, so that as the snipper knife 114 moves against and past the back of the gage 106 it snips or shears through the edge of the stock. The movement of the snipper knife 25 is secured by suitable mechanism from the main shaft 12. In the construction illustrated the snipper knife 114 is adjustably mounted by the set screw 115 in a snipper arm 116 swinging in the slot 117 of the 30 guide 56 and fulcrumed on the pin 118. It projects up through the slot in the projection 111 of the overhanging arm. An arm 119 projects to the left from and is connected with the arm 116 and carries at its 35 end a ball head 120, so that when this arm 120 is rocked up and down the snipper knife will be swung back and forth against the back of the gage 106. A spring pressed pin 121 adjustably secured by the set screw 122 in the top flange of the casing presses 40 against the arm 119, and an adjustable screw 123 carried by an upward projection from the arm 116 engages the casing of the spring pressed pin 121 to limit the movement of the snipper knife. A frame 124 is 45 mounted to slide vertically in the casing 3 and is apertured at its upper end to allow the arm 119 to pass therethrough. The frame carries a sleeve 125 sliding in the upper flange of the casing 3 and this sleeve 50 contains a vertically adjustable pin 126 adapted to engage the top of the ball 120. Another pin 127 slides loosely vertically in the frame 124 and when in its uppermost position engages the bottom of the ball 120. 55 A cam slide 128 is mounted to slide horizontally in ways in the frame 124 and is cam shaped on its upper surface to engage a stud 129 projecting from the pin 127. The frame 124 is provided at its lower end 60 with horizontal projections 130 between which an eccentric 131 secured to the main shaft 12 operates. It will thus be seen that when the slide 128 is pulled to the rear it will engage the stud 129, raise the pin 127 65 into contact with the ball 120, so that the

ball will be held between the pin 127 and the pin 126, and then upon the rotation of the main shaft the frame 124 will be given a vertical reciprocation rocking the snipper knife.

The slide 128 is moved back and forth as required to secure the operation or cessation of operations of the snipper knife by connections with a knee lever 132 (see Fig. 9). In the construction shown this knee lever 75 132 is fulcrumed on the pin 133 on a plate 134 which may be secured to the bottom of the work table. Screw pins 135 limit the movement of the lever. A link 136 extends from the knee lever to the shorter arm of a 80 bell crank lever 137, the longer arm of which is in turn connected by a vertical link 138 with one arm of a bell crank lever 139 (see Fig. 1), the upper arm of which is pivoted at 140 to the rear end of the slide 128. A 85 spring 141 extending from the shorter arm of the bell crank lever 137 to a pin on the base plate 134 tends to maintain the parts in such position as to maintain the snipper knife out of operative connection with the 90 driving shaft, so that movement of the knee lever 132 is necessary to throw it into operative connection.

The snipper knife is held closely up 95 against the back of the gage by means of a hardened block 142 (shown in Fig. 2) adjustably secured in the overhanging arm 46 and by means of the longitudinal adjustment of the gage 106.

The general operation of the machine will 100 be apparent from the foregoing description. It will be seen that in the construction illustrated the operator with one foot controls the clutch for stopping and starting the machine, with the other foot controls the length of the feed, and with his knee throws into and out of operation the snipper knife. The parts projecting above the work plate are 105 small. The overhanging arm 46 is of small cross-section and the work may pass freely beneath the projection 111, so that vamps and other parts having a small opening may readily be manipulated to have the edge turned.

When the edge is folded around an inside 115 or concave curve, as illustrated in Fig. 14, it is desirable and usually necessary to snip the folded edge producing the effect shown in the figure referred to.

The operation of folding an edge about 120 a convex or outside curve, particularly when this curve is sharp, is an extremely difficult one. Such work is customarily performed by hand, the operator plaiting the edge into small folds. An important feature of this invention is that it enables this class of work to be done rapidly and efficiently by machine. This class of work is illustrated in Fig. 15 which shows the heel portion of an upper with the edge folded 125 130

over, including the folding at four convex or outside curves. The construction and operation of the machine by which this highly desirable result is secured may well be emphasized. At the conclusion of a given feeding operation the work is held with the last completely folded portion clamped between the fold presser 23 and the pressing block 22, with the yielding work support 19 depressed and the folding finger 21 retracted. The yielding work support 19 then rises, clamping the body of the work between itself and the fold guide or creaser 20, and at the same time the fold presser 23 rises, releasing the work from between the fold presser 23 and the pressing block 22, but leaving the edge cemented down. Thus the work is free to turn about the edge or toe of the fold guide or creaser 20, thus enabling the edge to be turned on a very sharp convex or outside curve. With the work thus held clamped between the yielding work support 19 and the fold guide or creaser 20, and the folded edge cemented down to the body of the work, at a distance rearwardly equal to the length of feed, the folding finger 21 moves up on an incline in the plane of and across the toe or edge of the fold guide or creaser 20 and turns the edge of the work thereover, forming a pucker or buckle in this edge between where it is cemented down to the body of the work and where it is held between the fold guide or creaser 20 and the folding finger 21, the yielding work support 19 having been depressed during the upward movement of the folding finger 21. During this turning of the edge by the folding finger 21 the fold presser 23 and pressing block 22 have moved forward close up to the folding finger 21, and the fold presser has started on its downward or clamping movement, and while the work is held between the fold guide or creaser 20 and the folding finger 21, the fold presser 23 comes down directly over the pucker formed in the edge and presses it down upon the pressing block 22, so that the pucker lies in a plait over toward the previously folded portion of the edge. While the fold presser 23 is coming down thus to clamp the edge the folding finger 21 begins to be retracted. When the fold presser 23 has clamped the puckered edge against the pressing block 22 and the folding finger 21 is retracted clear of the fold guide or creaser 20 so as to release the work, the feed takes place by the movement of the fold presser 23 and pressing block 22 rearwardly and the operation proceeds as before.

The machine of the present application in some of its aspects is an improvement upon the machine of my Patent No. 1,224,529;

and certain features, which are shown

and described in the present application, are claimed in the patent.

Having fully described my invention, what I claim as new and desire to secure by Letters Patent is:

1. A machine of the character described comprising means for progressively folding the edge of a piece of material, means for pressing the folded edge upon the body of the material and means for increasing such pressure automatically during the passage of the material through the machine.

2. A machine of the character described comprising means for progressively folding the edge of a piece of material, a pressing block and a fold presser between which the fold is completed, means for bodily moving the pressing block and fold presser to feed the material and means for increasing the pressure of the fold presser upon the pressing block during the feeding movement.

3. A machine of the character described comprising a work table, a fold guide or creaser mounted above the work table with its edge in the line of feed of the material, a folding finger supported beneath the work table and reciprocable across the edge of the fold guide in a direction inclined to said edge, and means for reciprocating said folding finger to turn the edge more than ninety degrees about the fold guide.

4. A machine of the character described comprising a work table and fold guide or creaser supported above the work table, a folding finger coöoperating with the fold guide or creaser to initiate the fold, mounted and operated from beneath the work table, means for completing and setting the fold mounted and operated from beneath the work table, and means for snipping the edge prior to folding mounted and operated from beneath the work table.

5. A machine for progressively folding the margin of a piece of sheet material having pressing mechanism and folding mechanism in combination with a gage having a curved face, a pivoted presser located above said gage and a spring for holding said presser and gage in contact.

6. A machine of the character described comprising a folding guide or creaser, a folding finger and means for moving the folding finger across the edge of the fold guide and in the vertical plane thereof to initiate the fold, and means for supporting the creaser above the material to allow the creaser to yield vertically and laterally and maintain the same width of fold in crossing seams and other obstructions.

7. A machine of the character described comprising a work table, a supporting arm projecting therefrom, a fold guide or creaser mounted on said supporting arm to yield vertically and laterally, a folding finger and means for moving the folding finger across

- the edge of the fold guide to initiate the fold, a fixed gage having a curved face to guide the edge of the material to the fold guide and folding finger, and a yieldingly mounted fold presser gage coöperating with said fixed gage and having its face conforming to the face of the fixed gage.
8. A machine of the character described comprising a fixed gage, a coöperating yieldingly mounted presser gage, the adjacent faces of said gages conforming and coöperating to guide and turn the edge of the material, a work support mounted to yield vertically, a fold guide or creaser supported above the work support and mounted to yield vertically and laterally, a folding finger, and means for moving the folding finger across the edge of the fold guide to turn the edge of the material.
- 10 9. A machine of the character described comprising a fixed gage, a coöperating yieldingly mounted presser gage, the adjacent faces of said gages conforming and coöperating to guide and turn the edge of the material, a work support mounted to yield vertically, a fold guide or creaser supported above the work support and mounted to yield vertically and laterally, a folding finger, and means for moving the folding finger across the edge of the fold guide to turn the edge of the material, a pressing block, and a yielding fold presser coöperating with said pressing block to complete and set the fold.
- 15 10. A machine of the character described comprising a fixed gage, a coöperating yieldingly mounted presser gage, the adjacent faces of said gages conforming and coöperating to guide and turn the edge of the material, a work support mounted to yield vertically, a fold guide or creaser supported above the work support and mounted to yield vertically and laterally, a folding finger, and means for moving the folding finger across the edge of the fold guide to turn the edge of the material, a pressing block, a yielding fold presser coöperating with said pressing block to complete and set the fold, and means for bodily moving the pressing block and fold presser to feed the material.
- 20 11. A machine of the character described comprising a fixed gage, a coöperating yieldingly mounted presser gage, the adjacent faces of said gages conforming and coöperating to guide and turn the edge of the material, a work support mounted to yield vertically, a fold guide or creaser supported above the work support and mounted to yield vertically and laterally, a folding finger, and means for moving the folding finger across the edge of the fold guide to turn the edge of the material, a pressing block, a yielding fold presser coöperating with said pressing block to complete and set the fold, and means for bodily moving the pressing block and fold presser to feed the material.
- 25 12. A machine of the character described comprising a fold guide or creaser, a folding finger and means for reciprocating it across the fold guide or creaser to turn the edge of the work thereover, means for causing the fold guide or creaser and the folding finger yieldingly to hold the turned edge, a pressing block and coöperating fold presser and means for causing the said pressing block and fold presser to act upon the turned edge between the point where it is held by the fold guide or creaser and the folding finger and where it has been previously cemented down upon the body of the work, thus setting a pucker or plait in the edge and permitting the folding of the edge about a convex or outside curve.
- 30 13. A machine of the character described comprising a fold guide or creaser, a folding finger and means for reciprocating it across the fold guide or creaser to turn the edge of the work thereover, means for causing the fold guide or creaser and the folding finger yieldingly to hold the turned edge, and means acting upon the turned edge between the point where it is held by the fold guide or creaser and the folding finger and where it has been previously cemented down upon the body of the work to complete the turning of the edge, to set a pucker or plait therein, and thus permit the folding of the edge about a convex or outside curve.
- 35 14. A machine of the character described comprising a fold guide or creaser, a folding finger, means for moving the finger relatively to the creaser to turn the edge of the work thereover and hold the work yieldingly, and means acting between the point where the work is thus held and the point where the edge has been previously cemented down to complete the turning of the edge and to press the edge upon the body of the work.
- 40 15. A machine of the character described comprising a work table, a fold guide or creaser mounted above the work table with its edge in the line of feed of the material, a folding finger supported beneath the work table and reciprocable across the edge of the fold guide in a direction inclined to said edge, means for reciprocating said folding finger to turn the edge more than ninety degrees about the fold guide, means for feeding the material and means for varying the rate of feed during the operation of the machine.
- 45 16. A machine of the character described having, in combination, a work table, a folder and a creaser located opposite each other and both held from movement in the direction of feed of the work, said folder being supported beneath the table and ref 130

ciprocable across the edge of the fold guide in a direction inclined thereto, and means for reciprocating said folder to turn the edge more than ninety degrees about the fold guide.

17. A machine of the character described comprising a work table, a fold guide or creaser mounted above the work table with its edge in the line of feed of the material, 10 a folding finger supported beneath the work table and reciprocable in a straight line path across the edge of the fold guide and in a direction inclined to the plane of said table, and means for reciprocating said folding finger.

18. A machine for progressively folding the margin of a piece of sheet material having, in combination, a work table, an arm projecting over said table, a creaser carried 20 by said arm, a presser, a folder and a knife extending up through said table, and mechanism located beneath said table for actuating said knife, folder and presser.

19. A machine for progressively folding 25 the margin of a piece of sheet material having, in combination, means for intermittently feeding a piece of material into position to have its margin folded, a creaser for defining the line of fold, a folder arranged to 30 bend the margin of the material about the edge of the creaser, a presser for completing and pressing the fold, a work support located beneath the creaser, and means for intermittently raising said work support to 35 grip the material between it and said creaser.

20. A machine for progressively folding and plaiting the convexly curved margin of a piece of sheet material having, in combination, means for feeding a piece of leather 40 intermittently into position to have its margin folded, a member to press upon the leather and thereby determine the line of fold, a movable folder opposite said member and arranged to coöperate therewith to initiate 45 the fold, and a hammer located close to and beside the folder whereby in a convexly curved margin a pucker is formed by the folder beneath the hammer, in position to be engaged by said hammer when said hammer is brought down.

21. A machine of the character described having, in combination, a work table, a folder and a creaser, located opposite each other and both held from movement in the direction of feed of the work, said folder being supported beneath the table and reciprocable across the edge of the fold guide in a direction inclined thereto, means for reciprocating said folder to turn the edge more 50 than ninety degrees about the fold guide, means for feeding the work, and means for varying the rate of feed during the operation of the machine.

22. A machine of the class described comprising a fixed gage having a curved oper-

ative face, said gage being provided with a shoulder, a pivoted presser gage having an operative face curved to correspond to the curvature of said fixed gage, and a spring for holding said presser gage down upon 70 said shoulder.

23. A machine for progressively folding and pressing the margin of a piece of flexible material, having, in combination, a support for the material, means for forming the fold, combined pressing and feeding mechanism separate from the folding means, and means for causing said mechanism first to press the fold and then to feed the material.

24. A machine for progressively folding 80 and pressing the margin of a piece of flexible material, having, in combination, a stationary creaser, a folder reciprocable in an inclined path to coöperate with the creaser in forming the fold, a presser for pressing the fold, and means for moving the presser in a direction transverse to its pressing movement to feed the material.

25. In a folding machine a gage having an upwardly curved face, and a coöoperating gage extending over said first-named gage whereby the width of the margin which is to be folded over on the body of the work is determined.

26. A machine for progressively folding 95 and plaiting the convexly curved margin of flexible material comprising means engaging said flexible material to feed it, a stationary member shaped to cause the margin of the material as said material is fed past 100 it to be bent upwardly with the edge of said material uppermost, a movable finger acting upon the margin so bent to form an upstanding pucker therein and a presser acting to swing the bent margin with its upstanding pucker down upon the body of the material.

27. A machine for progressively folding 110 and plaiting the convexly curved margin of flexible material, comprising means for curving upwardly the margin of the material with respect to the body thereof, movable means for forming a pucker in said upwardly curved margin, said upwardly curved pucker being unsupported 115 and out of contact with the body of the material, and means for contacting with said pucker in said upwardly curved margin and pressing it down upon the body of the material in the form of a plait.

28. A machine for progressively folding 120 and plaiting the convexly curved margin of a piece of flexible material comprising a stationary member with a curved face for partially curving the margin, a fold presser and a device movable up and down in a path at right angles to the line of fold and acting to form a pucker in the partially curved margin.

29. A machine of the class described hav-

- ing, in combination, a folder for partially forming the fold, mechanism for feeding the stock intermittently past the folder, mechanism for completing and pressing the fold, 5 and means for operating said feed and pressing mechanisms, said means comprising a shaft, a plurality of levers pivoted about said shaft, an operating shaft, a plurality of cams on said last named shaft arranged to oscillate said levers, and means for rotating said operating shaft.
30. A machine of the class described having, in combination, a table for supporting the stock, means for forming the fold, stock 10 feeding mechanism, pressing mechanism, and means for operating said mechanisms, said means including a plurality of parallel shafts located beneath said table, one of said shafts being a pivot shaft and the other an operating shaft, cams on said operating shaft, a plurality of levers supported at a point near one end on the pivot shaft and at a point spaced from said end by said cams, and means for rotating said operating shaft.
25. 31. A machine of the class described, having, in combination, a table for supporting a piece of stock, feeding means, a stationary member arranged to turn up the margin of the stock fed past it, a presser arranged to 20 act upon the margin after the action of the stationary member, and means for operating said feeding means and presser, said operating means including two parallel shafts located beneath said table, a plurality of levers connected with said shafts, means for rotating one of said shafts, and cams mounted on said rotating shaft and adapted when said shaft is rotated to oscillate said levers about the axis of the other shaft.
30. 32. A machine for progressively folding the margin of a piece of flexible material comprising a stationary member past which the material is fed to curve upwardly the margin of said material, a knife to snip said 35 upwardly curved margin, means for vibrating said knife in a path located entirely above the plane of the body of the material, and a reciprocating presser, said knife being located between said stationary member and said presser.
33. A machine of the class described, having in combination, means for feeding a piece of flexible material into position to have its margin operated upon, a stationary 40 member having a curved face for bending upwardly said margin, a knife located in the rear of said member and adapted to snip the bent-up margin, means for vibrating
- said knife in a path located entirely above the plane of the body of the material, and 60 a reciprocating presser located in the rear of said snipping knife.
34. A machine for progressively folding the convexly curved margin of a piece of flexible material comprising means engaging said material to feed it, a stationary member for turning up the margin of the material into a position in which the edge is uppermost, a movable member for turning the margin farther in the same direction and at the same time forming an upstanding pucker in the margin, and means acting subsequently to lay the upstanding pucker upon the body of the material in the form of a plait. 70
35. A machine of the class described having, in combination, a table to support the stock, feed mechanism, snipping mechanism and pressing mechanism arranged to act upon the stock so supported, an operating shaft located beneath said table, cams on said shaft, connections from said cams respectively to said feed mechanism, said snipping mechanism, and said pressing mechanism, and means for rotating said 85 operating shaft.
36. A machine for progressively folding the margin of a piece of flexible material, comprising a stationary member past which the material is fed to curve upwardly the 90 margin of said material, a knife to snip the upwardly curved margin, means for vibrating said knife in a path approximately parallel to the plane of the body of the material, and a reciprocating fold presser, said 95 knife being located between said stationary member and said presser.
37. A machine for progressively folding the margin of a piece of flexible material, comprising a stationary member having an 100 upwardly curved face past which the material is fed to curve the margin of the material upwardly into an approximately vertical position, a knife, means for vibrating said knife to slit said upwardly curved margin, and a reciprocating fold presser, said 105 knife being located between said stationary member and said presser.
- In testimony whereof I have signed my name to this specification in the presence of 110 two subscribing witnesses.
